UNITED STATES PATENT OFFICE.

FRED PARKER LEONARD, OF TAUNTON, MASSACHUSETTS.

DESIGN FOR AN OVEN-DOOR.

SPECIFICATION forming part of Design No. 33,837, dated January 1, 1901.

Application filed December 7, 1900. Serial No. 39,100. Term of patent 7 years.

To all whom it may concern:

Be it known that I, FRED PARKER LEONARD, a citizen of the United States, residing at Taunton, in the county of Bristol and State of Massachusetts, have produced a new and original Design for an Oven-Door, of which the following is a specification.

This invention relates to a new and original design for an oven-door, and the essential feature of the design resides in the door, as illustrated in the accompanying drawing, which is a perspective view of an oven-door embodying the design.

The numeral 1 designates the body of the door, which has a rectangular contour and beveled edges. On the outer face of the said body, adjacent opposite ends, are acanthus scrolls 2, having a solid appearance and rising from lower outwardly-directed scrolls 3, having spaces between them and also in the form of conventional leaves. The upper terminals 4 of the scrolls 2 are inturned and directed downwardly on opposite sides of the

center of the body vertically considered. From the inner limit of the outwardly-directed scrolls 3 conventional leaves similar to those forming the latter scrolls are directed inwardly to produce enlarged spirals 5 to provide a lower central ornament partially rising above the inner curved margins in regular lines, as at 6, of the scrolls 2 and the outwardly-directed scrolls 3. The said margins inclose a panel 7, and at one end of the latter is a representation of a looped rope length 8, turned at an angle to form a handle.

Having thus described the invention, what is claimed as new is—

The design for an oven-door, herein shown and described.

In testimony that I claim the foregoing as my own I have hereto affixed my signature in the presence of two witnesses.

FRED PARKER LEONARD.
